By Victor J. Evans,

Attorney,

UNITED STATES PATENT OFFICE.

ZALA RIDDLE, OF DUNSMUIR, CALIFORNIA

WATCHMAKER'S JEWELING-TOOL.

1,230,032.

Specification of Letters Patent. Patented June 12, 1917.

Application filed April 26, 1915, Serial No. 24,044. Renewed January 23, 1917. Serial No. 144,050.

To all whom it may concern:

Be it known that I, ZALA RIDDLE, a citizen of the United States, residing at Duns-
5 muir, in the county of Siskiyou and State
of California, have invented new and useful
Improvements in Watchmakers' Jeweling-
Tools, of which the following is a specification.

This invention is an improved watch-
10 maker's jewelng tool, by means of which
the seat in the jewel setting for a watch
may be cut in three operations and without
any chance of making a mistake after the
jeweling tool has been set.

15 The invention consists in the construction,
combination and arrangement of de-
vices, hereinafter described and claimed.

In the accompanying drawings;

20 Figure 1 is a plan, on an enlarged scale,
of a watchmaker's jewelng tool constructed
in accordance with my invention.

Fig. 2 is a longitudinal sectional view of
the same.

25 Figs. 3 and 4 are transverse sectional
views of the same on the lines *a—a* and *b—b*
respectively of Fig. 1.

The body of my improved watchmaker's
jeweling tool is of oblong rectangular form
30 and is here shown as comprising a pair of
arms 2 connected together, in spaced relation,
and parallel with each other, by a cross
bar 3 at their outer ends and which is here
shown as secured thereto by screws 4. This
35 cross bar is provided on one side, at the
center, with a fixed flange or jaw 5. A
block 6 is rigidly secured between the arms
2 at a point a suitable distance from the
outer end or cross bar 3 by screws 7. A
block 8 is arranged for movement toward
40 and from the bar 3 and in the space between
the arms 2 and is operated by a screw 9
which is journaled in the block 6, has
threaded engagement with a bore in the
movable block 8 and is provided with a
45 milled operating wheel 10 arranged in the
space between the blocks 6 and 8, one side
of the said wheel being engaged in a recess
11 in one of the arms 2. A jaw 12 is se-
cured on the movable block 8 by screws
50 13 and is movable, by said block 8, and the
screw shaft 9, toward and from the fixed
jaw 5.

A block 14 is arranged between the arms
2, extends to one of the ends of the body and
55 is provided with a tapered shank 15 which
is adapted to fit the tail stock of the lathe

in connection with which my jewelng tool
is used. The block 14 is movable laterally
in the space between the arms 2 of the body
and is mounted on a pair of transversely ar-
ranged shafts 16 which pass through trans-
verse bores in said block 14, the ends of said
shafts being suitably secured in the arms 2.
A screw 17 is provided for adjusting the
block 14, is swivelly mounted in one of the 65
arms 2, has threaded engagement with a
transverse bore in the block 14 and is pro-
vided at its outer end with knurled head 18
whereby it may be readily turned by the
thumb and forefinger to effect the desired 70
adjustment of the block 14 in the space be-
tween the arms 2. This block 14 is provided
on one side, near its front end, with a flange
19 that extends outwardly therefrom and
forms a jaw. 75

Said jaw 19 is movable in an L-shaped
slot 20 in a plate 21 which extends across
the arms 2 and the block 14 and is adjust-
ably secured on said arms by means of
screws 22, 23 which are respectively ar-
ranged in slots 24, 25 with which said plate
is provided. The screw 23 has an enlarged
knurled head 26 by means of which it may
be readily turned. A gage wire 27 extends
across the slot 20 at the point where the arms 80
28 enters the enlarged rectangular body 29
of said slot. This gage wire is spaced from
the block 14 a distance nearly equal to the
thickness of the plate 21, said gage wire hav-
ing its ends secured in slits in the outer 85
surface of said plate 21.

On the outer end of the body 1 is a chuck
30 which is provided with a thumb screw
31 and which holds a bit 32 that has two
cutting edges 33, 34. 95

The operation of my improved jewelng
tool is as follows: With a tool 35 which has
at one end a thin strip 36, a jewel is picked
up, this being done by moistening the thin
strip by applying it to the thumb, and then
100 applying the moistened strip to the jewel,
and causing the latter to stick to the strip.
The jewel and the strip are then placed ver-
tically between the gage jaws 5, 12 and said
jaws are closed on the strip and jewel, by
105 moving the block 8 by means of the screw 9
and wheel 10. The jaw 12 is moved until
the jewel and strip are tightly clamped, thus
setting the gage formed by the jaws 5 and
110 12 ready for use. The jewel is then picked
up with a pair of tweezers and placed flat on
the block 14 in the enlarged portion 29 of

the slot 20 and between the jaw 19 and the L-arm 28 of said slot. The plate 21 is then adjusted, after loosening the screws 22, 23 until the side of the slot pushes the jewel 5 up to the jaw 19. The thumb screw 23 is then tightened, thus securing the plate 21 in adjusted position. With the tweezers the jewel is then pushed to the right, its position being observed by the use of a double lens. 10 The screw 17 is then turned to the right, by means of its knurled head 18 until the jewel has been backed by the jaw 19 half way under the gage wire 27. The jewel is then removed and the setting stock is then put in 15 the chuck in the lathe. The jewelng tool is then run up to the setting, until the double edged bit 32 touches the same. The tail stock is then fastened by the liner on the side and while the lathe is running at high 20 speed the knurled wheel 10 is turned to the right as far as practicable. The thumb screw 18 is then turned to the left as far as practicable, the seat being thus cut to both the required depth and diameter. The 25 jewelng tool is then pulled out of the setting and the screw 18 turned to the right until it opens the tool to the required extent and the bezel for the jewel is then cut.

My improved jewelng tool is simple in 30 construction and enables all watch jewels to be readily set, without reference to their varying sizes.

Having thus described my invention I claim:—

35 1. A watch maker's jewelng tool having a chuck at its outer end for a double edged bit and also having a fixed gage jaw at its outer end, a movable block mounted in the body and having a jaw, means to adjust said block 40 and its jaw, a block mounted in the body for transverse movement and having a jaw on one side and also provided at its outer end with a shank whereby the tool may be at-

tached to a chuck, means to adjust the last named block, a plate extending across the 45 body and the last named block and adjustable transversely of said body and block, said plate having an L-slot in the larger portion of which the jaw of said last named body is arranged, and a gage wire extending 50 across the inner end of the L-arm of said slot and spaced from said last named block.

2. A watch maker's jewelng tool comprising a body having a slot near its outer end and a second slot extending at its inner 55 end, a jaw at the outer end and on one side of the body, a chuck at said end of the body having a double edged bit, a block mounted for movement in the first named slot of the body and having a jaw to move therewith toward and from the first named jaw, a screw shaft to operate said block and having an operating wheel, a second block mounted for transverse movement in the second slot of the body, provided at its inner end with a shank adapted to be engaged by a lathe chuck, said second block also having a jaw on one side near its outer end, a screw for adjusting said second block in the second slot and thereby relatively moving 65 the body transversely with respect to said second block, and a plate extending across the body and said second block, adjustable transversely thereof, provided with an L-slot, in the larger portion of which said jaw 70 of the second block is arranged, said plate being further provided with a gage wire extending across the inner end of the L-arm of its slot and spaced from the said second block.

80 In testimony whereof I affix my signature in presence of two witnesses.

ZALA RIDDLE.
